AWNNG BELT CENTER SUPPORT

Henry C. Heiser, Parma, Ohio, assignor to The Astrup Company, Cleveland, Ohio, a corporation of Ohio

Application November 24, 1941, Serial No. 420,195

5 Claims. (Cl. 242—73.5)

The invention relates generally to center supports for roller awnings, and more particularly to a center support embodying an endless belt on which the awning roll and the canvas rolled thereon is carried.

Awnings rolls vary considerably in diameter and the center support for the awning roll should accordingly be capable of adjustment to accommodate and properly support various sizes of awning rolls. Also the pitch of the awning when extended varies considerably in accordance with the requirements of installation and operation of the awning, and the center support should accordingly be adapted to meet the requirements in change of pitch.

In awning center supports in which the awning roll is supported on underlying rollers or upon an endless belt encircling the rollers, there is a definite tendency as the awning is unrolled for the awning roll to ride up over the front supporting roller, or the belt, at that point, and this tendency causes undue friction between the awning roll and the supporting belt and consequent wear on both the awning and the belt.

It is therefore a general object of the present invention to provide an awning center support which meets the foregoing requirements and overcomes the difficulties of prior constructions.

More specifically, it is an object to provide a belt center support having adjusting means to accommodate various sizes of awning rolls.

Another object is to provide a belt center support having adjusting means to accommodate changes in pitch of the awning when extended.

A further object is to provide a belt center support which is adapted to form a pocket in the belt for the awning roll in such a position as to cause a minimum of friction and prevent wear on the awning and the belt.

A still further object is to provide an awning center support which is particularly well adapted for use in an awning recess box which houses the awning when it is rolled.

And finally, it is an object to provide an improved belt type center support for an awning roll, which support is easily installed and adjusted to meet varying conditions in size and pitch of awnings.

These and other objects are accomplished by the improvements comprising the present invention which may be stated in general terms as including a wall bracket with an upper guide roller arm adjustable thereon, and a roller belt supporting arm movably mounted thereon, the endless belt for supporting the awning roll being mounted

on a cradle which is rockable on the supporting arm.

Referring to the drawings forming part hereof,

Figure 1 is a side elevation partly in section of one embodiment of the improved belt center support as on line 1—1, in Fig. 2;

Fig. 2 is a front elevation thereof with parts broken away.

Fig. 3 is a fragmentary sectional view as on line 3—3, Fig. 2;

Fig. 4 is an elevation view similar to Fig. 1 of a modified form of center support; and

Fig. 5 is a front elevation thereof.

Similar numerals refer to similar parts throughout the drawings.

Referring first to the embodiment of the invention shown in Figs. 1, 2 and 3, the improved center support preferably includes a wall bracket or plate 6 which is adapted to be mounted upon a suitable support by means of the bolts or screws 7, and which has a cut-out portion 6'. As shown the wall bracket is mounted on a channel 8 which may be supported in a usual manner in an awning recess box.

At the upper end of the wall bracket 6 an overlying guide roller arm 9 is adjustably mounted for projecting outwardly over the awning roll 10. Preferably the overlying arm 9 has an inclined portion 11 for conforming to the underside of the leg of the channel 8 provided in an awning recess box, although this would not be necessary if the center support were mounted on a different supporting member. At the outer end portion of the underlying arm 9 a guide roller 12 is journaled, said guide roller being preferably journaled in a bracket 13 which has a tubular portion 14 slidably on the arm 9, with a set screw 15 screwed into the tubular portion 14 for securing the guide roller at any desired position along the arm 9.

The inner end of the arm 9 has a depending flange portion 16 which is forked and fits downwardly over a bolt 17 which is screwed into the wall bracket 6. Thus by loosening the bolt 17, the projecting arm 9 can be raised or lowered to accommodate different sizes of awning rolls and also to adjust the guide roller vertically to accommodate changes in pitch of the extended awning. By adjusting the arm 9 vertically and the guide roller 12 horizontally on the arm 9, a wide variation of awning roll sizes and changes of pitch can be accommodated.

Near the lower end of the wall bracket 6 and at the central portion laterally thereof, projecting ears 18 are provided forming a yoke to which the underlying or lower supporting arm 19 is

pivotedly connected as at 20. The arm 19 is provided at its inner end with a depending ear 21 through which an adjusting screw 22 is threaded and the end of which abuts the wall bracket 6. The adjusting screw 22 may be provided with a lock nut 23 for holding the screw in any desired position, and by loosening the lock nut and screwing the screw 22 in or out the arm 19 is raised or lowered about the pivot 20.

The cradle for journaling the belt rollers in this embodiment is indicated generally at C and preferably includes arcuate side bars 24 in the ends of which the belt rollers 25 are journaled, and an endless belt 26 is wrapped around the belt rollers 25, the upper run of the belt extending directly from one to the other of said rollers and being adapted to support an awning roll 10 between the rollers as shown in Fig. 1.

The pivotal connection at 20 is purposely made loose enough to allow a slight rocking movement of the cradle C laterally as viewed in Fig. 2 for insuring that the upper surface of the belt adjusts itself to the plane of the awning roll 10, that is, so that the axes of rollers 25 are parallel with the axis of the awning roll.

The arcuate side bars preferably have inwardly projecting lugs 27 on their inner surfaces, and a transverse plate 28 is supported on and secured to said lugs. Means for pivotally supporting the cradle on the supporting arm 19 preferably includes a yoke having two arms 29 depending from an upper platform 30. The transverse plate 28 is supported on and secured to the platform 30 and the depending arms 29 of the yoke straddle the outer ends of arm 19 and are pivotally secured thereto as by the bolt 31.

Preferably, the pivotal connection at 31 is located slightly off center with respect to belt rollers 25, as shown in Fig. 1, so that by reversing the cradle it can accommodate various sizes of awning rolls.

Means for permitting tilting adjustment of the cradle with respect to the supporting arm 19 and for holding the cradle in adjusted position preferably includes a bolt 32 passing through the lower ends of the yoke arms 29 and through an elongated arcuate slot 33 in the outer end of arm 19 below the pivot 31.

In the installation of the improved center support, the guide roller 12 is removed from the upper arm 9 by loosening the set screw 15, whereupon the awning roll can be inserted and placed upon the belt 26. The guide roller 12 is then mounted on the arm 9 and its position as well as the vertical position of the arm 9 on the bracket 6 is adjusted to suit the size of the awning roll and the degree of pitch of the awning which is desired.

If further adjustment is required to accommodate the awning roll size or pitch, this is effected by manipulation of the adjusting screw 22 to raise or lower the lower support arm 19, and when the desired adjusted position is reached, the arm 19 may be firmly held in place by tightening the lock nut 23 on the adjusting screw 22. In order to "pocket" the awning roll, that is, to cause the upper run of the belt 26 to rollably support the awning roll between the rollers 25 in such a manner as to counteract the tendency of the awning roll to ride over the front roller, and to produce a minimum amount of friction between the belt and the awning roll, the cradle may be adjusted by manipulating the bolt 32 to slightly tilt the cradle so that the front belt roller is elevated with respect to the rear belt roller.

Thus the improved center support provides a simple and effective support for the center of the awning roll between its ends, and provides means for quickly and easily adjusting the various parts thereof to accommodate changes in the sizes of the awning roll and in the pitch of the awning, as well as to provide for supporting the awning roll with a minimum of friction as the awning is being unrolled and with a consequent minimum amount of wear on the awning roll and the supporting belt therefor. It is noted that in this embodiment of the invention the lower supporting arm 19 can be adjusted up or down by manipulating a single adjusting screw 22, and the cradle can be tilted by adjusting a single bolt 32.

Referring to the modified form of the improved center support illustrated in Figs. 4 and 5, the general construction of this embodiment is similar to the embodiment of Figs. 1, 2 and 3 and includes a wall bracket 6a adapted to be mounted on a suitable support by means of bolts or screws 7a. As shown the wall bracket 6a is mounted on a channel 8a incorporated in an awning recess box, and a guide roller arm 9a is mounted on the upper end of the wall bracket and conforms to the underside of the upper leg of the channel 8a.

The guide roller arm 9a has a guide roller 12a adjustably mounted on its outer end and a set screw 15a is provided for securing the guide roller in adjusted position on the arm 9a. The inner end of the arm 9a has a depending flange portion 16a which is adjustably secured to the upper end of the wall bracket 6a by means of a screw 17a, whereby the arm 9a can be raised or lowered to accommodate different sizes of awning rolls or different degrees of pitch in the extended awning.

The wall bracket 6a is provided near its lower end with projecting ears 18a located at opposite sides of the wall bracket to which underlying supporting arms 19a are pivotally connected as at 20a, and the supporting arms 19a are provided with depending ears 21a through which adjusting screws 22a are screwed with their inner ends abutting the wall bracket 6a.

The cradle for journaling the belt rollers in this embodiment is indicated generally at C' and preferably includes arcuate side bars 24a in the ends of which belt rollers 25a are journaled, and an endless belt 26a is wrapped around the belt rollers in such a manner that the upper run of the belt is adapted to support an awning roll 10a between the rollers.

The arcuate side bars 24a are pivotally connected to the outer projecting ends of the supporting arms 19a by bolts 31a, and this pivotal connection is preferably off center with respect to the belt rollers, that is, closer to the rear belt roller 25a than to the front belt roller 25a. Below the pivots 31a, the side bars 24a are provided with depending ears 35a which are movably connected to the outer ends of supporting arms 19a by means of bolts 32a passing through the ears 35a and through elongated arcuate slots 33a in the outer ends of arms 19a.

The installation and operation of the center support shown in Figs. 4 and 5 is generally the same as in the embodiment shown in Figs. 1, 2 and 3, with the exception that adjustment of the supporting arms 19a requires manipulation of two screws 22a, and rockable adjustment of the cradle C' requires manipulation of two bolts 32a.

I claim:

1. A roller awning center support including a

wall bracket adapted for attachment to a support, an overlying arm adjustably mounted thereon, a guide roller mounted on said arm for horizontal adjustment relative thereto, an underlying support arm pivotally mounted on said wall bracket, means for adjusting said support arm toward and away from said overlying arm, a belt roller cradle rockably mounted on said support arm, rollers journaled in the ends of said cradle, an endless belt trained around said rollers for supporting an awning roll, and means securing said cradle in adjusting position on said arm.

2. A roller awning center support including a wall bracket adapted for attachment to a support, an underlying support arm pivotally mounted on said wall bracket, means for adjusting said support arm, a belt roller cradle rockably mounted on said support arm and having rollers journaled in its ends, an endless belt trained around and extending directly between said rollers for supporting an awning roll, and means securing said cradle in adjusted position on said arm.

3. A roller awning center support including a wall bracket adapted for attachment to a support, an overlying arm vertically adjustably mounted thereon, a guide roller mounted on said arm for horizontal adjustment relative thereto, an underlying support arm pivotally mounted on said wall bracket, single means for adjusting said support arm toward and away from said overlying arm, a belt roller cradle rockably mounted on said support arm and having rollers journaled in its ends, an endless belt trained around said

rollers and extending directly from one to the other of said rollers for supporting an awning roll, and single means for securing said cradle in adjusted position on said arm.

5. 4. A roller awning center support including a wall bracket adapted for attachment to a support, an overlying arm adjustably mounted thereon, a guide roller mounted on said arm for horizontal adjustment relative thereto, an underlying support arm pivotally mounted on said wall bracket and projecting outwardly therefrom, an adjusting screw in the support arm abutting said wall bracket for raising and lowering said arm, a roller belt cradle pivotally mounted on the outer end of said support arm and having rollers wholly supporting an endless belt, and means for limiting the pivotal movement of said belt cradle on said support arm.

20 5. A roller awning center support including a wall bracket adapted for attachment to a support, an underlying support arm pivotally mounted on said wall bracket, means for adjusting the position of said support arm relative to said wall bracket, a roller belt cradle, spaced rollers journaled in said cradle, an endless belt wrapped around said rollers and adapted for supporting an awning roll, means intermediate and spaced at unequal distances from the belt rollers reversably and rockably supporting said cradle on said support arm, and means for securing said cradle in adjusted position on said support arm.

HENRY C. HEISER.
